UNITED STATES PATENT OFFICE.

HENRY A. SPRENGER, OF DETROIT, MICHIGAN, ASSIGNOR TO JOSEPH SPRENGER AND SONS, A COPARTNERSHIP DOING BUSINESS IN DETROIT, MICHIGAN.

BOILER.

1,164,884.

Specification of Letters Patent. Patented Dec. 21, 1915.

Application filed March 11, 1914. Serial No. 823,931.

To all whom it may concern:

Be it known that I, HENRY A. SPRENGER, a citizen of the United States of America, residing at Detroit, in the county of Wayne 5 and State of Michigan, have invented certain new and useful Improvements in Boilers, of which the following is a specification, reference being had therein to the accompanying drawings.

10 In the construction of steam boilers and especially those for marine use in which the space is necessarily restricted, it is desirable that the parts be so disposed as to be readily accessible for cleaning and that the 15 boiler be sufficiently rigid to withstand the oscillations to which it is subjected.

This invention relates to boilers and to an arrangement thereof whereby they are 20 readily accessible for cleaning, present large radiating surfaces in and around the combustion chamber and are extremely rigid without being complicated.

The invention consists in the matters hereinafter set forth and more particularly 25 pointed out in the appended claims.

In the drawings, Figure 1 is a view in transverse section of a form of boiler that embodies features of the invention; Fig. 2 is a view in longitudinal section taken on 30 or about line II—II of Fig. 1; Fig. 3 is a view in front elevation, partially broken away of the boiler; Fig. 4 is a view in section taken on or about line IV—IV of Fig. 3, parts being broken away; Fig. 5 is a 35 view in transverse section of a modified form of the invention; and Fig. 6 is a view taken on or about line VI—VI of Fig. 5.

Referring to the drawings, a front water leg 1 and rear water leg 2 are connected by 40 a series of water tubes 3 disposed on either side of the structure and upper water tubes 4. A pair of steam drums 5 also connect the upper portion of the legs. A grate space below fire doors 6 in the front water legs is spanned by suitable bars 7 and is 45 cut off from the rear connections of the boiler by a transverse bridge wall 8. A flue shell 9 is secured in a suitable opening in the rear wall 10 of the front water leg and extends rearwardly therefrom over the 50 grate space. The head 11 that closes the back end of the drum is at an interval from the rear water leg 2 and is in direct communication therewith through a mud drum 55 12 connected by a fitting 13 with the bot-

tom of the drum and secured in a suitable opening of the forward wall 14 of the rear water leg. The flue shell and mud drum rest upon a suitable cradle 16 that is supported as by masonry or a cross beam 17 60 back of the bridge wall 8.

Flue tubes 19 extend through the shell 9 and are secured in the usual manner in the front wall 20 of the front water leg thereby discharging into the smoke breeching 21 65 that is mounted on the front water leg. A steam pipe 22 connects the upper portions of the water legs between the drums 5 with a suitable delivery pipe 23 leading therefrom. A hand hole plate 24 in the rear 70 wall 25 of the rear water leg 2 permits ready access to the drum 12. Suitable stay members 26 (Fig. 5) of any preferred construction may connect the drums 5 with the flue shell 9 to steady the latter. A jacket 75 27 forms the side walls of the furnace. Preferably the latter consists of a suitable fire proof lining 28 such as asbestos, or the like, with an outer metal sheathing of any preferred type. The jacket 27 extends to 80 the drums 5 while the space between the latter and over the water tubes 4 is closed by another section 29 of the jacket. This may be supported independently of or rest on the water tubes 4. Suitable hand hole 85 plates, one of which is indicated diagrammatically at 30, are placed in the rear water leg and front water leg opposite each of the water tubes 3 and 4 and other hand hole and man-hole plates are provided wherever 90 it is desired. The water legs are further stiffened by stay bolts, not shown. Wher- 95 ever needed, the usual accessories of boiler construction are added.

In the modifications shown in Figs. 5 and 95 6, a series of water tubes 31 are disposed to connect the front and rear water legs, the upper tubes being substantially on the same plane with a series of auxiliary water tubes 32 that are disposed between the forward 100 wall of the rear water leg and the head 33 of the flue shell. In such modification, a jacket 34 that is adjacent the water tubes is supported by suitable means so as to abut against the flue shell and to bridge the space 105 over the auxiliary water tube 32 between the rear end of the flue shell and the rear water leg as indicated in Fig. 6.

As a result of this construction a boiler is 110 obtained that presents a very large surface

for absorption of the heat of the gases of combustion, the latter passing upwardly against the water tubes and around the shell and then outwardly through the flues of the shell into the breeching. Because of the position of the steam pipe between the upper shells or drums, the boiler can be tilted laterally through a very wide arc without in any way encroaching upon the steam space so that the delivery is always uniform regardless of any oscillations of the boiler.

The boiler is particularly efficient because of its large radiating surface and its compact structure which permits it to be readily cleansed, the disposition of parts being such that they are readily accessible at all times. The boiler is extremely rigid and does not tend to start its seams or strain the joints when oscillated, as there are no great bodies of water whose inertia must be resisted.

Obviously, changes in the details of construction may be made without departing from the spirit of the invention and I do not care to limit myself to any particular form or arrangement of parts.

What I claim is:—

1. A boiler comprising a front water leg, a rear water leg, series of water tubes connecting the legs near the sides thereof, a pair of drums connecting the upper portions of the legs, a transversely disposed bridge wall between the lower end portions of the water legs forming a grate space adjacent the front water leg, a cradle back of the bridge wall, a mud drum extending forward from the rear water leg and resting on the cradle, a flue shell extending inwardly from the rear wall of the front water leg and having communication with the mud drum on which it is supported, flues in the shell extending through the front wall of the front water leg, a smoke breeching on the front water leg in communication with the flues, a steam pipe in communication with the water legs above the normal level of the contents of the steam drums and a jacket extending between the water legs and inclosing the water tubes and flue shell.

2. A boiler comprising a front water leg, a rear water leg, steam drums connecting the upper portions of the water legs, a series of water tubes connecting the water legs along the margins and across the upper portions

thereof, a transverse bridge wall between the lower portions of the water legs forming a grate space back of the front water leg, a mud drum extending from the front wall of the rear water leg toward the bridge wall, a cradle supporting the outer end portion of the mud drum, a flue shell extending from an opening in the rear wall of the front water leg over the bridge wall and above the mud drum on which it is supported, flue tubes extending through the shell and the front wall of the front water leg in which they are secured, a smoke breeching on the front water leg in communication with the flue tubes and a steam pipe in communication with the upper portions of the water legs and a jacket extending between the front and rear water legs outside the water tubes, the rear head of the flue shell being at an interval from the adjacent wall of the rear water leg.

3. A boiler comprising an upright front water leg provided with fire doors near its base, an upright rear water leg, a pair of steam drums connecting the upper portions of the water legs, water tubes disposed along the margins and across the upper portions of the water legs with which they are in communication, a transverse bridge wall between the lower portions of the water legs forming a grate space back of the fire doors, grate bars spanning the space, a cradle between the bridge wall and the rear water leg, a mud drum extending forwardly from the front wall of the rear water leg and resting on the cradle, a flue shell whose front end portion is secured in an opening in the rear wall of the front water leg and whose rear head is at an interval from the rear water leg, the flue shell being in communication with the mud drum on which it is supported, flue tubes extending from the rear head of the shell through the front wall of the front water leg, a smoke breeching on the front water leg in communication with the flue tubes and an insulating jacket inclosing the water tubes.

In testimony whereof I affix my signature in presence of two witnesses.

HENRY A. SPRENGER.
